UNITED STATES PATENT OFFICE.

WILLIAM DAVID FRICKS, OF ATLANTA, GEORGIA.

KEY-LOCK FOR TYPE-WRITERS.

No. 892,242.

Specification of Letters Patent. Patented June 30, 1908.

Application filed July 8, 1907. Serial No. 382,762.

To all whom it may concern:

Be it known that I, WILLIAM DAVID FRICKS, a citizen of the United States, residing at Atlanta, in the county of Fulton and State of Georgia, have invented certain new and useful Improvements in Key-Locks for Type-Writers; and I do hereby declare the following to be a full, clear, and exact description of the invention, such as will enable others skilled in the art to which it appertains to make and use the same.

This invention relates to improvements in key locks for typewriters, and the object in view is the provision of means for automatically setting the key lock when adjusting a paper finger.

With this and further objects in view, the invention comprises the combination of a typewriter having a movable carriage, a paper finger adjustable longitudinally thereof, typewriter keys operating in conjunction with said carriage, and means, adapted to be actuated by the paper finger, for locking the keys against movement.

The invention further comprises certain other novel constructions, combinations and arrangements of parts as will be hereinafter fully specified and claimed.

In the accompanying drawings:—Figure 1 is a view in front elevation of a typewriter, portions of the machine being broken away for illustrating parts in the rear. Fig. 2 is a transverse section taken on the plane indicated by line 2, 2 of Fig. 1, the ribbon guide being omitted, and parts of the machine being seen in elevation. Fig. 3 is a perspective view of fragments of the machine, illustrating the present invention applied thereto.

The present invention has for the sake of convenience been illustrated as applied to a typewriter such as is being placed on the market by Messrs. L. C. Smith & Bros. Typewriter Co., but it will become obvious, from the following description, that the invention may readily be applied to any of the standard typewriters.

It is quite common in the best makes of typewriters to employ some means for locking the keys of the typewriter at the time the carriage arrives at the extreme of its movement to the left, or, in other words, at the conclusion of a line, so that a number of imprints of different type on the same spot cannot be made. The devices employed for thus locking the keys have been known as line

locks or key locks, and in some instances have been made adjustable, so that where the operator wishes to terminate the line short of the length of the platen, he may set his line lock accordingly, and if he is using paper of less width than the length of the platen, or of less width than the width of the paper previously used, he will find it necessary to adjust at least one of the paper fingers.

The present invention obviates the necessity for separate adjustment of the line lock and paper finger, the line lock being automatically adjusted with any adjustment of the right hand paper finger.

Referring to the drawing by numerals, 1 indicates the framework of the machine upon which is mounted a carriage 2, provided with the usual platen 3' disposed in the rear and above the usual type well. A bar 3 is fixed to the carriage 2 and extends parallel to the platen 3' throughout the length thereof and in front of the same. Paper fingers 4 and 5 are slidingly carried by the bar 3, each through the medium of a plate 6 slidably clamped about the bar 3 and pivotally connected to the respective paper fingers, a spring 7 being provided for each paper finger for maintaining the same normally in engagement with the platen. A right angle flange or ear 8 extends from one edge of the paper finger 5 for facilitating shifting of the same longitudinally of the platen 3'. Each of the fingers 4 and 5 is provided with the usual gripping roller 9. In the ordinary construction of a typewriter, a graduated plate or bar 10 is secured in front of the bar 3 and spaced a sufficient distance therefrom for permitting the clamp 6 to slide. Clamp 6 of course in fact constitutes a part of the respective paper finger, and is provided with a depending lug 85 or projection 12.

As the bar 3 is fixed to the carriage 2, the paper finger 5 will of course move with the carriage during its movement, and in the path of movement of the projection 12 is arranged the outer end of a crank arm or crank 13, which crank is fixed to or formed integral with a shaft 14. The shaft 14 is journaled in bearings 15, 15 fixed to portions of the frame 1 independently of carriage 2. The rear end of the shaft 14 is provided with a right angle portion which is suitably pivotally connected with a depending bar 16. The lower end of the bar 16 extends loosely through the front portion of line lock bail 17 110

of the machine, and is provided with an adjusting nut 18 resting upon said bail. A lock nut 19 is also threaded onto the rod 16 and, in operation, is threaded down tightly 5 upon the nut 18 for retaining the same against accidental movement.

The line locking bail 17 is pivotally mounted on standards 20, 20 fixed in the frame of the machine, said bail at one end being provided with an upturned flange 21, engaged by a laterally acting spring 22 which presses the flange 21 rearwardly and thus elevates the front edge of the bail. Journaled in suitable bearings in the frame 1 is a rod or shaft 23, extending upwardly from which are arms 24, 24 pivotally carrying the universal bar 25. Fixed to the bar 25 and extending rearwardly therefrom is a rod 26 which is arranged to transmit movement to the escapement mechanism of the carriage. The rod 26 extends beneath the bail 17 and a projection 27 extends upwardly from said rod contiguous to said bail 17, the projection being formed at its upper end with a seat 28 disposed beneath the bail 17 and a projection 29 extending at the front of said bail and a little below the horizontal plane of the elevated front edge thereof.

In front of the universal bar 25 are arranged the usual type bar actuating levers 30, connected with and actuated by the keys 31 in the usual manner. In operation, when any particular key 31 is depressed, the upper portion of the corresponding lever 30 is moved rearwardly for elevating its type bar, and, during said rearward movement, the lever 30 strikes the universal bar 25 and moves the same rearwardly, thus actuating the carriage release for permitting movement of the carriage immediately after being struck by the type of the particular bar actuated. Thus it will be obvious that with each depression of a key 31, the bar 26 must move rearwardly and the projection 29 thus be moved beneath the bail 17. In the particular machine illustrated, means are provided for releasing the pressure of the spring 22, when the carriage 2 arrives at the termination of its movement toward the left, and, of course, as soon as such pressure is released, the bail 17 will drop down upon the seat 28 and will prevent rearward movement of the projection 29, so that the keys 31 are effectually locked against operation.

From the foregoing it will be readily obvious that during the operation of the machine, when the carriage 2 is moved toward the left until the projection or lug 12 strikes the outer end of the crank 13, the further movement of such lug toward the left will rotate the shaft 14 a sufficient distance for depressing the rod 16, and as the nut 18 is already in contact with the front edge of the bail 17, the bail will be depressed into the path of movement of the projection 29 and thus lock

the keys 31 against operation, it being obvious, of course, that in depressing the front edge of the bail 17 the pressure of the spring 22 must be overcome. Thus it is seen that by merely shifting the paper finger 5 to any desired point along the length of the platen 3, the line lock or key lock will be immediately set to correspond with the width of column or paper corresponding with that represented by the position of the paper finger. No adjustment of any other parts than the paper finger is required.

The pressure exerted by the spring 22, in the machine illustrated, is very slight and is only sufficient for sustaining the front edge of the bail 17 elevated, so that the pressure exerted by the projection 12 on the crank 13 is reduced to a minimum, and therefore in practice I find that the friction between the paper finger 5 and surrounding parts, is more than ample to overcome any resistance of the crank 13. Obviously, when the carriage is moved to the right and the projection 12 leaves crank 13, the spring 22 will immediately elevate the front edge of bail 17 to its normal position.

While I have illustrated the present invention as applied to a specific and well known standard typewriter, it is obvious, of course, that the invention is applicable to all of the various forms of typewriters, and I wish the terms of the appended claims construed to comprehend typewriters generically.

What I claim is:

1. In a typewriter, a movable carriage, and a paper finger moving therewith, a pivotally mounted line lock bail, a spring normally maintaining one edge of said bail in an elevated position, a key actuated projection movable beneath the elevated edge of said line lock bail, an adjustable rod supported on the elevated edge of said bail and a horizontal rock shaft engaged by the paper finger for depressing the adjustable rod and lowering the normally elevated edge of the bail into the path of movement of said projection.

2. In a typewriter, the combination of a movable carriage, a paper finger moving therewith, a pivotally mounted line lock bail, a spring normally maintaining one edge of said bail in an elevated position, a universal bar, an arm connecting the same with the carriage escapement, a projection carried by said arm and movable beneath the elevated edge of said bail, an adjustable rod supported on the elevated edge of said bail and a horizontal rock shaft engaged by the paper finger for depressing the adjustable rod and lowering the normally elevated edge of the bail into the path of movement of said projection.

3. In a typewriter, the combination of a movable carriage, a paper finger connected thereto, a pivotally mounted line lock bail, a spring normally maintaining one edge of said

bail in an elevated position, a series of key levers, a universal bar actuated thereby, an arm connecting the universal bar with the carriage escapement, a projection carried by 5 said arm and movable therewith, an adjustable rod supported on the elevated edge of the bail, and a horizontal rock shaft engaged by the paper finger for depressing said adjustable rod and lowering the normally ele-

vated edge of the bail into the path of move- 10
ment of said projection.

In testimony whereof I affix my signature in presence of two witnesses.

WILLIAM DAVID FRICKS.
